MECHANICAL PENCIL

Lucifer J. Most, Morris County, N. J.

Application September 12, 1947, Serial No. 773,619

8 Claims. (Cl. 120—18)

1

My invention relates to mechanical pencils, and the object thereof is to provide a non-revolvable tip with means for actuating the lead feed normally operable from a turning tip, to improve the performance of the lead feed from such means in a non-revolvable tip, to enhance the appearance of a pencil equipped with such a tip and make this type of a tip more adaptable to different styling of pencil barrels.

Another object of the invention is to provide a mechanical pencil feed mechanism which forms a unit with the tip, permitting the use of such unit with a great variety of barrels of any configuration and color.

Still another object of the invention is to obviate the failures common with mechanical pencils having a revolvable tip in contrast with a fixed one, that is, non-revolvable relatively to the barrel.

A further object of the invention is to provide a lead actuating mechanism carried by the tip, independent of a pencil barrel, and operable from a finger grip accessible through the lateral surface openings of the tip.

In the appended drawing forming part of this application,

Figure 1 is a fragmentary elevation of a tip end of a mechanical pencil embodying my invention.

Figure 2 is a tip end elevation of same.

Figure 3 is a fragmentary vertical section on lines 3—3 of Figure 1.

Figure 4 is a cross section on lines 4—4, Figure 1, and

Figure 5 is a cross section on lines 5—5, Figure 3.

Referring to the drawing, 10 is a tip having a lead outlet 11 extending from the tip end to an inner counterbore 12. A guide 13 in the form of a tube slotted lengthwise through a portion of it has its lower non-slotted end entering the counterbore 12. The said counterbore leads into the smaller end of a tapered bore 14 which has openings 15 through the lateral periphery of the tip between its end 16 and 17.

A driver 18 in the shape of a truncated conical sleeve is housed within the bore 14 to turn freely and its tapered periphery is knurled to provide a finger grip through the openings 15. The bore 19 of the driver 18 has a force fit with the un-slotted portion of the guide 13 to couple them into a unit.

The driver 18 and the guide 13 are preassembled and placed into the tip 10 through the larger end 16 bringing the driver into the bore 14 and the lower end of the guide 13 into the counterbore

12, while the slotted end of the guide projects above the driver and extends out of the tip through its larger end 16.

A counterbore 20 is formed in the end 16 of the tip 10 above the larger end of the tapered bore 14. Force fitted into the counterbore is the larger end of a sleeve 22 while the reduced end 23 of the sleeve is made to project above the tip end to provide a plug for connecting the tip to an end 24 of a barrel 25 with a snug fit so that the tip 10 will not turn in the barrel.

The bore 26 of the sleeve 22 has a forced fit with the lower end of a tubular helix 27, to which it is therefore rigidly secured. The tubular helix houses therein the slotted guide 13 with a free running fit when the sleeve with the helix anchored thereto is forced into the counterbore 20 of the tip.

The guide 13 houses therein a freely sliding tubular lead clutch 28, the upper end of which is provided with a laterally directed pin 29 passing through the slot 13' of the guide 13 to engage the helical grooves 27' of the helix 27. A push bar 30 within the tubular lead clutch 28 is mounted to move freely therein; it has one end projecting out above the clutch and thereat has a lateral extension 31 passing through the guide slot 13' of the guide 13 and entering the helical groove 27' of the helix 27, one convolution above the pin 29 of the lead clutch.

In normal operating condition, the lower end of the push bar 30 is above the lower end of the tubular lead clutch 28 to permit the clutch portion thereof to grip the end of a lead 32 below the push bar 30. To permit the push bar to expel the lead 32 from the clutch through the outlet 11 of the tip, the lower end of the helical groove is continuous with a section of a circular groove 33, see Figure 3.

The circular groove section 33 is lying in a plane perpendicular to the axis of the helix, and when engaging therein the pin 29 of the lead clutch 28, the clutch will not move longitudinally when the driver 18 and the guide 13 are turned, but as the pin 31 of the push bar 30 is still engaged in the helical groove 27', it will move longitudinally, pushing out the lead portion engaged by the clutch.

Whether the driver is coupled to the guide 13 or the helix 27, it revolves relative to the tip in which it is mounted. The entire lead actuating mechanism described is carried by the tip and is operable in the tip through the driver 18 whether connected or not to a barrel through the medium

of plug 23 of sleeve 22 forming a rigid part of the tip.

I claim:

1. A lead actuating mechanism for a mechanical pencil comprising, a tip having a lateral opening, a rotatable driver in the tip accessible through the lateral opening of the tip, a lead actuating mechanism having parts thereof coupled respectively to the driver and the tip and tip securing means for coupling it, non-rotatably to a pencil barrel end.

2. A lead actuating mechanism for a mechanical pencil comprising, a tip having lateral openings, a rotatable driver in the tip accessible through the lateral openings of the tip, a plug coupled to the tip above the driver to prevent the driver from moving longitudinally in the tip, a lead actuating mechanism having parts thereof coupled respectively to the driver and the plug, said plug projecting above the tip for securing the tip non-rotatably to an end of a pencil barrel.

3. A lead actuating mechanism for a mechanical pencil comprising, a tip having lateral openings, a rotatable driver in the tip accessible through the lateral openings of the tip, a plug coupled to the tip above the driver to prevent the driver from moving longitudinally in the tip, a lead actuating mechanism including a tubular helix and a tubular slotted guide coupled to the plug and driver respectively, said plug projecting above the tip to provide means for coupling the tip non-rotatably to an end of the barrel.

4. A lead actuating mechanism for a mechanical pencil comprising, a tip having a lead outlet and a tapered bore above the outlet, a truncated driver knurled on its tapered periphery revolubly mounted in the tapered bore, said tip having lateral openings giving access to the knurled surface of the driver, a plug coupled to the tip above the driver to prevent longitudinal movement of the driver in the tip and a lead guiding mechanism including a tubular helix and a tubular slotted guide coupled to the plug and driver respectively, said plug extending above the tip to connect it firmly to an end of a pencil barrel.

5. A lead actuating mechanism for a mechanical pencil comprising, a tip having a lead outlet and a tapered bore above the outlet, a truncated driver knurled on its tapered periphery revolubly mounted in the tapered bore, said tip having lateral openings giving access to the knurled surface of the driver, a plug coupled to the tip

above the driver to prevent longitudinal movement of the driver in the tip, said plug having an axial opening, a tubular helix secured in the bore, and projecting out of the plug above the tip, said driver having an axial bore, a lengthwise slotted tubular guide revolubly mounted in the helix and fixed in the bore of the driver to participate in the movement of the driver, a lead clutch in the guide and a push bar in the clutch, said clutch and bar having lateral pins passing through the slot of the guide and engaging the helix, said plug extending above the tip and serving as means for connecting firmly the tip to an end of a pencil barrel.

15 6. A lead actuating mechanism for a mechanical pencil comprising, a tip having a lead outlet and a tapered bore above the outlet, a truncated driver knurled on its tapered periphery and revolubly mounted in the tapered bore but prevented from moving laterally, said tip having lateral openings giving access to the knurled surface of the driver for rotation thereof only, a plug coupled to the tip above the driver to prevent the driver from longitudinal movement in the tip and a lead actuating mechanism having parts thereof coupled respectively to the driver and the tip, said plug extending above the tip to connect it firmly to an end of a pencil barrel.

20 7. A lead actuating mechanism for a mechanical pencil comprising, a tip having a lateral opening, a rotatable driver in the tip accessible from the lateral opening of the tip for rotation only, said driver being prevented from moving in the tip either laterally or longitudinally, a lead actuating mechanism having parts thereof coupled respectively to the driver and the tip, said tip having a projection above the driver for securing the tip non-rotatably to an end of a pencil barrel.

25 8. A lead actuating mechanism for a mechanical pencil comprising, a tip having a lead outlet and a tapered bore above the outlet, a truncated driver knurled on its tapered periphery, revolubly mounted in the tapered bore but prevented from moving therein either laterally or longitudinally, said tip having lateral openings giving access to the knurled surface of the driver for rotation thereof only, and a lead actuating mechanism having parts thereof coupled respectively to the driver and the tip, said tip having means for connecting it firmly to an end of a pencil barrel.
